UNITED STATES PATENT OFFICE.

HARVEY W. HASCY, OF KINGHAM, MASSACHUSETTS, ASSIGNOR TO JOHN L. WHITING-J. J. ADAMS CO., OF BOSTON, MASSACHUSETTS, A CORPORATION OF MASSACHUSETTS.

TUFT SOCKET.

Application filed October 26, 1923. Serial No. 670,845.

This invention relates to tuft sockets such as used in the construction of brushes to hold knots or tufts of bristles and to connect them to the brush back. The invention 5 particularly relates to that type of tuft sockets disclosed in Letters Patent of the United States, No. 1,465,893, granted August 23, 1923 to Frederick S. Chanonhouse, on which the present invention is an improvement.

As disclosed in said patent, the tuft socket consists of a small ferrule or sleeve, open at both ends, slightly tapered from end to end and provided at its larger end with a permanent flange. The socket with a tuft of bristles inserted therein is placed within the brush back and subjected to the pressure of a die which is provided with a tapered bore adapted to encircle the socket, the diameter 20 of said bore at the entrance thereof being slightly less than the diameter of the socket adjacent to its permanent flange, but the taper of said bore being greater than the original taper of the socket. The die is slid 25 longitudinally of the socket thereby compressing the smaller end of the socket upon the tuft of bristles. This compression of the smaller end of the socket is resisted by the bristle tufts, which resistance causes a 30 strong outward pressure to be exerted by the bristles upon the upper edge of the socket. During this compression, however, those portions of the side walls of the socket adjacent to its upper edge are supported, or clamped as it were, between the 35 compact mass of bristles and the walls of the die, so that the sliding movement of the die longitudinally of the socket produces a drawing of the socket metal towards the 40 larger end thereof, with the result that an outward bulge of the socket metal occurs at the end of the die, which bulge is forced by the die into engagement with the brush back to form a bead which cooperates with 45 the permanent flange to hold the socket, and the bristles contained therein, securely in position upon said back. The diameter of the smaller end of the socket is thus contracted by the above operation, the drawing 50 action of the die causing surplus metal resulting from such contraction to be forced towards said bead so that when the socket is finally clamped in position, the side walls thereof are smooth and free from corrugations.

The operation of the die and the contraction of the socket metal thereby has proven satisfactory. It has been found, however, that after the operation of the die and the assembly of the brush is completed, the 60 sockets develop a tendency occasionally to split at the smaller ends thereof where the compression of the bristles is the greatest. I have discovered that this splitting is probably attributable to the fact that the 65 pressure of the bristles is exerted laterally against a free edge of the socket metal in such a manner that the metal edge is subjected to a tearing action. The problem of constructing the socket so that the pressure 70 of the bristles would not be exerted against a free edge of the socket metal was complicated by the necessity for retaining the smooth tapered wall of the socket in order that the compressing die could act thereon 75 in the manner disclosed in the patent and also by the necessity for keeping the socket metal, particularly at the smaller end thereof, in a condition such that the surplus metal due to the contraction could be drawn 80 or forced longitudinally towards the larger end to form the clamping bead.

The object of the present invention is to construct a tuft socket capable of being compressed about a tuft of bristles and clamped 85 to a brush back in the manner disclosed in the said patent to Frederick S. Chanonhouse, No. 1,465,893, and in which the objectionable splitting of the sockets is overcome.

In the accompanying drawings, which illustrate an example of the invention without defining its limits, Fig. 1 is an elevation of the tuft socket on an enlarged scale; Fig. 2 is a section thereof on 95 the line 2-2 of Fig. 1 showing the socket, with a knot of bristles therein, connected with the brush-back and Figs. 3, 4 and 5 are diagrammatic views illustrating various stages in the operation of making the socket. 100

As shown in the aforementioned patent and also in the accompanying drawings, the socket is constructed of thin sheet metal, preferably annealed so as to render the metal ductile. The socket is shaped to form 105 a ferrule 10 open at both ends and provided with a permanent flange at one of its ends; from this flange the side wall or body of the socket tapers slightly toward its opposite end.

In order that the essential characteristics of the socket disclosed in the patent may be retained, while at the same time the splitting of the sockets may be overcome, I bend 5 the upper free edge of the socket back upon and in close contact with the side walls thereof as indicated by the numeral 12, thus removing, as it were, the free edge of the metal from the zone of greatest pressure of 10 the bristles. This not only produces, as clearly shown in Fig. 2, a double rounded edge at the upper extremity of the socket, but also leaves the socket in such a condition that the metal thereof can be drawn 15 longitudinally by the compressing die. Furthermore, as the metal of the socket is quite thin and as the bent back portion is forced into contact with the side walls of the socket, said portion does not project outwardly too far to interfere with the drawing action of the die necessary for the formation of the clamping head 18.

The bending back of the small end of the socket may be accomplished in any convenient manner as, for instance, in successive 25 steps with the aid of suitable dies as shown in Figs. 3, 4, and 5 respectively. That is to say, the ferrule 10 may be supported upon a die 13 in registry with a co-operating die 30 14 whereby the unflanged end of the ferrule is turned outwardly to form an outwardly extending flange *a* as shown in Fig. 4; by one or more dies such as 15 this flange *a* is gradually folded to the position indicated at *b* in Fig. 5 and is finally folded into 35 surface engagement with the body of the ferrule by means of said die 15 to form the completed bent-back portion 12 as shown in Fig. 1.

40 After the socket has been formed as shown in Fig. 1, the knot of bristles 16 is placed

therein and treated with a rubber solution which is then vulcanized, as more fully set forth in said patent. The socket containing 45 the bristles is then inserted in the brush back and subjected to the action of the compressing die which contracts the small end of the socket and presses it tightly around the bristle tuft. During this action of the die the metal of the socket is bulged outwardly at the end of the die by the outward pressure of the bristles, the bulge so produced being drawn or forced longitudinally 50 of the socket by the end of the die to form the head 18 which is pressed firmly into 55 engagement with the brush back 17 and cooperates with the permanent flange 11 to hold the socket firmly and securely to said brush back.

It will be understood that the metal of 60 the socket 10 may be turned inwardly upon itself to form the reinforcement 11 interiorly of the socket 10 instead of outwardly as shown and described.

I claim:—

65 In a brush, one or more tufts of bristles, a socket pressed into clamping engagement with, and about the base of, each of said tufts to securely compress the same therein, said socket comprising a thin tapered ferrule of bendable material having a laterally projecting flange at its larger end, and a co-operating flange for clamping said socket to a brush-back, the terminal portion of the smaller end of said ferrule being bent downwardly into parallelism and into tightly 70 contacting engagement with, the side walls thereof for the purpose described.

75 In testimony whereof I have hereunto set my hand.

HARVEY W. HASCY.
